UNITED STATES PATENT OFFICE.

JOHN LAMAC, OF JAMESTOWN, NEW YORK.

COMBINED PICTURE-EXHIBITOR AND TABLE.

SPECIFICATION forming part of Letters Patent No. 623,164, dated April 18, 1899.

Application filed February 25, 1899. Serial No. 706,769. (No model.)

To all whom it may concern:

Be it known that I, JOHN LAMAC, a citizen of the United States, residing at Jamestown, in the county of Chautauqua and State of New York, have invented a new and useful Combined Picture-Exhibitor and Table, of which the following is a specification.

My invention relates to improvements in picture-exhibitors whereby the revolving case containing the pictures is hung in an opening in a table-top, which opening may be closed; and the objects of my improvement are, first, the combination and arrangement of the table-top and revolving case for the pictures, and, second, the means for retaining the pictures upon the holders in the case, as will be shown in the accompanying drawings, in which—

Figure 1 is a perspective view of table with revolving case in position in top. Fig. 2 is a sectional view of revolving case at line *x x* in Fig. 1. Fig. 3 is a sectional view of table-top at line *y y* in Fig. 1. Fig. 4 is a plan view of either side of a holder for the pictures.

In the drawings similar numerals in the several views refer to similar parts.

10 represents the frame of a table, and 11 the top of the same, which is hinged at 15 15 to the frame.

12 is the brace or support for the top to hold it at the desired angle of incline, and 13 the notches for the lower end of brace 12.

14 is an opening cut in top 11, and 14' is a slide which just fills the opening 14 and which 35 when closed makes a solid top for the table.

16 is a case for holding the photographs or pictures, and 17 (see Fig. 3) is a lug or block attached to the under side of top 11, but not to slide 14', strip 17' being placed across the 40 upper side of opening 14 on the under side of top 11 to receive block 17. On the opposite or lower side of opening 14 a like block is attached directly to the under side of top 11, as shown in dotted outline in Fig. 1, and each of 45 these blocks 17 17 form a bearing for a pin 18, attached to case 16 on its upper and lower sides, and on which case 16 revolves.

Case 16 may be made with one or more compartments; but each compartment must have 50 two openings 20 20 on each side (see Fig. 2) for viewing the pictures. The case shown in

Fig. 1 has four compartments, divided by the partitions 19 19. (Shown in dotted outline.)

21 22 is the holder for the pictures, 21 being the broad central part upon each side of which a picture is placed and which is made of thin wood or suitable material. 22 22 are the thicker end strips, which separate the central parts 21 sufficient to preclude any rubbing or touching of the pictures 24 or the elastic bands 60 23 23 with which the pictures are held in position on the holders, the bands 23 23 being placed at each end just inside of the projecting and beveled ends 22' 22' of strips 22 22. The holders are arranged in the well-known 65 manner of employing two odd-numbered tiers, the top holder sliding down to the lower side as the case revolves.

In use slide 14 is pulled out, as shown, uncovering opening 14 and case 16, which case 70 can then be revolved without raising top 11 to an incline, if desired, but when raised to the proper incline upon brace 12 the pictures are brought into the natural line of vision, and as case 16 revolves from side to side the 75 extra holder slides down from the upper to the lower side of each compartment, thus uncovering four new pictures in the four compartments with each half-turn.

My simplified holder, with the elastic bands 80 for holding the pictures, allows of the easy change of pictures, yet holds them securely in position, not allowing any slipping or sliding on the holder.

I claim as new—

In a picture-exhibitor and table, the pictures mounted on each side of the thin central portion of holders having thicker ends to slide upon, elastic bands around said holders and pictures to hold them in position, in combination with a hinged table-top provided with a revoluble case in which the picture-holders slide from side to side to bring the pictures alternately to view, substantially as shown and described.

In witness that I claim the foregoing I have hereunto subscribed my name in the presence of two witnesses.

JOHN LAMAC.

In presence of—

E. C. HUNT,
J. J. CRANDALL.
